United States Patent Office

Des. 222,355
Patented Oct. 19, 1971

222,355

DEODORIZER OR THE LIKE

Richard W. Farris, 1508 Indiana Ave.,
La Porte, Ind. 46350

Filed June 10, 1970, Ser. No. 23,413

Term of patent 14 years

Int. Cl. D23—04

U.S. Cl. D23—150

Fig. 1

Fig. 2

Fig 4

FIG. 1 is a front perspective view of a deodorizer or the like embodying my design;

FIG. 2 is a front elevational view thereof;

FIG. 3 is an elevational view of the side opposite that shown in FIG. 1; and

FIG. 4 is a rear elevational view thereof.

I claim:

The ornamental design for a deodorizer or the like, substantially as shown.
